UNITED STATES PATENT OFFICE.

THOMAS B. JEFFERY, OF RAVENSWOOD, ILLINOIS.

KEY-RECEPTACLE.

SPECIFICATION forming part of Letters Patent No. 405,843, dated June 25, 1889.

Application filed November 28, 1888. Serial No. 292,084. (No model.)

To all whom it may concern:

Be it known that I, THOMAS B. JEFFERY, a citizen of the United States, residing at Ravenswood, in the county of Cook and State of Illinois, have invented certain new and useful Improvements in Key-Receptacles, which are set forth in the following specification, reference being had to the accompanying drawings, forming a part thereof.

In the drawings, Figure 1 is a side elevation of my key-receptacle, shown in connection with the two abutting parts, which are supposed to be locked together by the lock to which the key in the receptacle pertains, said abutting parts being broken away to show the receptacle. Fig. 2 is a side elevation of the same device open, as in position for receiving or permitting the withdrawal of the key, and showing the key therein and partly withdrawn. Fig. 3 is a front view of the same, partly in section.

The purpose of this invention is to provide a suitable receptacle in which a key pertaining to the lock of a door, cabinet, drawer, or box may be deposited. This receptacle will most frequently be used in such position that it will not be accessible when the two parts are locked together—*i. e.*, when the door, box, or other article is closed—the entrance to it in such case being at the plane of the abutting edges or surfaces of the locking parts, and in this relation it is represented in Fig. 1. This, however, is not the only relation in which the device can be used; but it may often be found convenient to use such receptacle for the deposit of a key which is to be used by a number of persons who are all advised of its position, the receptacle being merely placed in a convenient but inconspicuous location. Secondly, my invention provides means for withdrawing the key from the receptacle, and incidentally I make the cover for the receptacle answer this purpose.

In the drawings, A represents a portion of one of the locked parts, as the door or door-jamb, box face or cover, drawer-head or cabinet-front. A' is a cavity in the part A, which, as illustrated, is provided with a metallic lining B. This, however, may be omitted. If employed, it is preferably attached to the face-plate C, which is designed to be let into and secured flush with the abutting surface of

the locked part A. E, in Fig. 1, represents the other abutting locked part. Through the face-plate C, I make the opening C', of such size as to admit one or more keys, preferably or most conveniently edgewise. To the face-plate C, I connect the lever C² by a pivot C³, and preferably make said lever wide enough to close the opening C'. I prefer to fit it into said opening so that when closed its surface will be flush with that of the face-plate C. I prefer, also, to pivot the lever C² to the plate by means of lugs c² and c', respectively thrown up upon the inner surface of each, so that nothing shall protrude from the outer surface of either. From the lever C² the projection C²⁰ extends into the cavity A'. Said projection has a lateral projection C²¹, extending transversely with respect to the cavity A', and, as illustrated, this projection consists of a small screw which is inserted through the projection C²⁰, and preferably allowed to protrude on both sides of it. Additional holes c²¹ may be made in the projection C²⁰, so that the screw C²¹ may be inserted at different positions. The lever C² extends below its pivot C³ a short distance, forming the tail or heel C²², and to the inner surface of the face-plate C there is secured the spring D, having one end bearing against the tail C²², and tending to force the lever toward the face-plate and hold it with the projection C²⁰ extending into the cavity A', and resist elastically the outward movement of the same.

F is the key, which is put in place by being first inserted longitudinally through the opening C' in the face-plate into the cavity A' far enough so that the projection C²¹ may enter the customary opening F' in the key-stem. The lever C² then being allowed to close, if wide enough to answer as a cover, conceals the key in the receptacle, and in any case holds it safely therein, and when it is desired to withdraw it the lever, being rocked outward, uncovers the opening C' and withdraws the key far enough so that it can be seized and removed. Preferably the projection C²¹ should be long enough to nearly touch the sides of the cavity A', so that the key cannot slip off over the end of said projection while in the cavity. Two keys may at the same time be retained in the device—one at each side of the projection C²⁰—operated by the two

ends, respectively, of the screw, whose said ends constitute the projections C²¹. The additional holes c²¹ in the projection C²⁰ are provided in order that the position of the projection C²⁰ may be adapted to the size of the key or the position of the opening F' therein.

Preferably the spring D is of such form and made to bear against the heel C²² at such point that the lever C² will not stay out except while it is forcibly held out, the spring at all times tending to rock it in. It is only necessary that the lever should rock out far enough to permit the key to be withdrawn past the projections C²⁰ and C²¹, and the shoulders c¹⁰ may be made on the lugs c² to stop the lever at that position and prevent it from being rocked so far over that the spring will not retract it. The reason for not allowing the lever to stand normally projecting is that if accidentally left in this position it might be broken off in the closing of the drawer or door.

I claim.

1. In combination with the two abutting parts adapted to be locked together, a key-receptacle in one of said parts having its entrance at the plane of their abutting edges, and a cover adapted to close said entrance, substantially as set forth.

2. In combination with the two abutting parts adapted to be locked together, a key-

receptacle in one of said parts having its entrance at the plane of their abutting edges, and a spring-actuated cover pivoted to such part and adapted to close said entrance, substantially as set forth.

3. In combination with the two abutting parts adapted to be locked together, a key-receptacle in one of said parts having its entrance at the plane of their abutting edges, and a key-withdrawing device jointed to the abutting part which contains said receptacle, and entering said receptacle and adapted to engage the key, substantially as set forth.

4. In a key-receptacle, in combination with a face-plate having an opening which serves as the entrance to said receptacle, a lever pivoted to the face-plate and adapted to close said opening, and having a projection adapted to engage the key and enter the opening when the lever is rocked toward the plate, substantially as set forth.

In testimony whereof I have hereunto set my hand, in the presence of two witnesses, at Chicago, Illinois, this 26th day of November, 1888.

THOS. B. JEFFERY.
